UNITED STATES PATENT OFFICE

CHARLES HENRI BICHLER, OF PARIS, FRANCE, ASSIGNOR TO THE FIRM AIR-SECURITE,
OF PARIS, FRANCE

BACK FIRE ARRESTER FOR COMBUSTIBLE GAS CONDUITS

Application filed December 27, 1927, Serial No. 242,866, and in France January 7, 1927.

My invention relates to the prevention of back firing in combustible gas conduits, by means of suitable channels or groups of channels, preferably parallel, which are provided in said conduits. The use of this device in the intake manifolds of internal combustion engines is especially advantageous.

One object of my said invention, comprises in combination, a combustible gas conduit whose diameter is slightly greater than is usual, and strips or sets of strips which are rigidly held in a suitable relative position in the said conduit, said device serving to prevent all back firing or entrance of flames, from whatever cause, into the gas supply holder or tank, whereby all accidents from this source will be prevented.

Another object of the said invention is to hold together, the said strips with suitable spacing, by means of bolts or like members which are provided with suitable cross-pieces or spacing members said strips being preferably secured at one end to a flange or collar which is attached by suitable means to a desired point on the suction piping.

Another object of said invention is to arrange the said bolts not in the interior of the set of strips, but at the ends of this set, in order to prevent all reduction of the flow section for the gas.

Another object of my invention is to conveniently arrange the said spacing members in order to avoid as completely as possible, eddies produced by said members in the moving combustible gas, which object is attained in providing, on said members, stream lined protuberances for preventing the said gases from eddying.

Moreover, said spacing members, instead of being provided in the middle part of the strips, are arranged at, or near the periphery of the bundles of strips, thus completely freeing the middle part or center of the pipe, with a view to considerably reduce the frictions and losses of speed of the gases in the suction pipe.

In the appended drawings which represent various embodiments of the invention:

Fig. 1 is an end view of an aeroplane engine embodying my invention,

Fig. 2 is a detail view, in axial section, showing the admission conduit according to the invention, mounted upon the engine shown in Fig. 1,

Fig. 3 is a side view of the same,

Fig. 4 is an end view of the sets of strips placed in the admission conduit,

Figs. 5 to 9 show vertical sectional views of variously perforated strips, hereinafter more fully described,

Fig. 10 is an elevational view of a set of strips disposed in a combustible gas conduit, which is shown in section,

Fig. 11 is a side view of a separate set of strips, with reference to Fig. 10,

Fig. 12 is a vertical cross sectional view of a spacing member,

Fig. 13 is an end view showing an arrangement of the spacing members near the periphery of the bundle of strips.

In accordance with the invention, each of the gas admission conduits comprises two parts 3 and 4 which are connected together by an elastic sleeve 5 consisting for instance of india rubber or the like. In my invention, one of the parts of the said admission conduit and preferably the part 4 which is directly connected with the cylinders 1 and 2, comprises in its interior a set of strips

The strips 6, are connected together by the bolts 7 provided with spacing members 8 which are mounted between the several strips so as to properly space them apart.

The bolts 7 are employed in any suitable number, and the width of the strips 6 progressively increases, as observed chiefly in Figs. 2 and 4 so that their lateral edges will be in tangential contact with their supporting sleeve or with the wall of the gas conduit in which they are disposed.

In these various constructions, the sets of strips may be placed in an adjustable position in the interior of the gas conduits. I may for instance bring the set of strips at any desired instant into the best position for the results to be obtained, and this adjustment may be employed with equal facility for strips situated in gas conduits whether under suction or pressure.

The dimensions of my device will of course vary with the size of the gas conduit with which it is used.

The sets of strips 6, may be secured in the gas conduit 4 by a bolt passing through suitable cross-pieces or spacing members in such manner that the bolt will also guide the said cross-pieces, and in this case one of the bolts 7 might be dispensed with. The strips of the set 6 may consist of any suitable substance, but I preferably employ a good heat-conducting metal, and the strips may be suitably polished to offer a minimum of resistance to the functioning of the conduit. The said strips may be perforated, and this may be effected by the punching process as shown in Fig. 5, the wall of the holes being perpendicular to the faces of the strips: but in order to prevent any opposition to the flow of the gas due to the suction of the engine, which might be occasioned by the impact of the gas upon the surfaces perpendicular to the flow, I provide sharp edges for the holes by the operation of countersinking which is performed on both faces as shown in Fig. 6, or on a single face as shown in Fig. 8, or by piercing said holes in an inclined direction as shown in Fig. 7 or by forming a thin edge or tongue at one side of the hole as shown in Fig. 9, said tongue preferably extending in the contrary direction to the flow of gas.

The number of perforations may vary according to the purpose for which the apparatus is utilized, and according to the particular conditions of each case.

As shown in Figs. 10 and 11, the strips 6 forming the protecting set which prevents back firing are provided at each end with lugs 16 and 17 for the insertion of respective bolts 18 separated by spacing members 19 of proper size; since the lugs 16 and 17 are formed at the ends of the strips, the bolts 18 securing the said strips will be situated outside the set of strips and will not diminish the flow section for the gas, and I thus appreciably reduce the prejudice which is offered by the device to the functioning of the engine, and the normal power

of the engine will thus be practically maintained.

The lugs 16 and 17 may have any desired form and may be employed in any suitable number, and into each lug I may insert two or more bolts if the strips are to be more rigidly held together, it is obvious that the said bolts are in all cases disposed outside of the set of strips.

In order to avoid as completely as possible the eddying of gases near the spacing members 19, the said members are provided as in Fig. 12 with projections 20, the ends 21 of which, receiving the impact of combustible gases which flow in the direction, of the arrow F in Fig. 12, are of a conveniently rounded cross section, with a shape similar to that of the entrance edge of an aeroplane wing. The rear ends 22 of said projections 20 are wedge-shaped, and end in a sharp line for preventing the gases from eddying.

My preferred arrangement is shown in Fig. 13, where in order to allow the speed of gases to be still higher, the central part of the gas pipe is cleared by arranging the spacing members together with their bolts near the periphery of the bundle of strips.

In using the apparatus herein described with an internal combustion engine, the sets of strips are disposed in each gas conduit in proximity to the engine and this disposition is advantageous due to the fact that it prevents the flames from entering the gas holders or generators from which the gases are supplied, thus obviating all the inconvenience and the danger which might occur from this source, such as melting of the pipes, loosening of the brazed flanges or joints, and the like, but it is obvious that the said sets of strips may be placed at any point along the admission piping.

The device herein described may be utilized as a fire-arrester in any combustible gas conduit, but it is especially useful in the intake manifolds of internal combustion engines, though I do not wish to be limited to its use therein.

What I claim is:

In a combustible gas conduit; a back fire arrester comprising an elongated bundle of spaced parallel strips inserted lengthwise in the conduit, the strips being provided with bolts passing through openings near their ends, elongated spacing members bolted between the strips, and said spacing members having a rounded front end and a wedge-shaped rear end.

In testimony whereof I have hereunto set my hand at Paris this tenth day of December 1927.

CHARLES HENRI BICHLER.
